UNITED STATES PATENT OFFICE.

WILLIAM BLACKMORE, OF CLEVELAND, OHIO, ASSIGNOR TO THE NATIONAL MALLEABLE CASTINGS COMPANY, OF CLEVELAND, OHIO, A CORPORATION OF OHIO.

COUPLING-YOKE.

1,239,764.

Specification of Letters Patent. Patented Sept. 11, 1917.

Application filed October 28, 1914. Serial No. 869,006.

To all whom it may concern:

Be it known that I, WILLIAM BLACKMORE, a citizen of the United States, residing at Cleveland, Cuyahoga county, Ohio, have invented new and useful Improvements in Coupling-Yokes, of which the following is a specification, reference being had to the accompanying drawings, in which—

Figure 1 is a bottom plan showing the application of my improved yoke to the underframing of a car; Fig. 2 is a side elevation, partly in section, thereof; Fig. 3 is a rear end view, and Fig. 4 is a front elevation thereof; Fig. 5 is a rear end view showing a modified form of the connection between the rear ends of the top and bottom members, and Fig. 6 is a partial side elevation thereof; Fig. 7 is a side elevation, partly in section, of another modification of my improved yoke, and Fig. 8 is a rear end view thereof; Fig. 9 is a plan of a further modification of my improved yoke; Fig. 10 is a side elevation thereof, partly in section; Fig. 11 is a rear end view of the modification shown in Fig. 10; Fig. 12 is a front elevation thereof; Fig. 13 is an elevation, partly in section, of a further modification of my invention, and Fig. 14 is a bottom plan thereof.

My invention relates to coupler yokes of the type intended to permit the convenient disengagement of the coupler, draft gear and yoke, and consists in providing a yoke in which the upper and lower arms of the yoke are suitably secured together at their rear ends, and also in providing their forward ends with mechanism to hold such ends in engagement with a coupler butt and to prevent spreading thereof under pulling stresses. My invention also consists in the construction and coöperation of the parts which I shall hereinafter describe and claim.

Referring to the drawings, A indicates the upper member or upper arm of the yoke, and B the lower member or lower arm, C a shackle or loop securing together the forward ends of the arms A and B, and D the coupler butt. The arm A is provided at its forward end with a pulling lip 2, intended

to engage the upper forward face 3 of the coupler butt D, and at its rear end by a 50 vertically disposed rear portion 4, and a rib 5 on the exterior of the arm A and its rear portion 4. At the lower end of the portion 4 the rib 5 is bifurcated to form a socket 6 open to the front, the rear and on its under side. The bottom and forward side of the socket 6 have, however, two laterally and inwardly extending curved flanges 7 which provide bearings for reception of the trunnions 8 on the thickened or reinforced portion 9, in which the rear end of the arm B terminates. The forward end of the arm B has an upwardly extending pulling lip 10, intended to engage a forward lower face 11 of the coupler butt D, and has also a key 60 receiving rib 12. The shackle C which encloses the forward ends of the yoke arms A and B is preferably of rectangular shape, and has on its upper side a lip or projection 13, which engages a shoulder 14 on the upper face of the upper arm A, and on its lower side it has downwardly extending apertured lugs 15, the apertures of which are intended to register with the aperture in the rib 12 of the arm B for reception of 65 a key or bolt 16. The shackle C has its side walls 17 offset or flared outwardly to permit lateral angling between the coupler and yoke.

In assembling the yoke the upper arm A 80 is held in position between the draft sills and the coupler butt D, over which the shackle C has previously been slipped, is inserted with its upper forward face 3 in contact with the lip 2 of the arm A. The followers 18 and shock absorbing mechanism may then be placed in position between the rear portion 4 of the arm A and the rear face of the coupler butt D. The trunnions 8 on the rear end of the arm B are then inserted from the rear into the socket 6 and are seated in the flanges 7, and the arm B may then be rotated upwardly until its pulling lip 10 engages the forward lower face 11 of the coupler butt D. The shackle C 85 may then be slid rearwardly from the cou-

pler shank, tilting its upper end to the rear (as is shown in the dotted line position in Fig. 2) so that the lip 13 will pass over the shoulder 14, when its lower end can be 5 swung downwardly to engage the lower side of the arm B and to bring the apertures in the lugs 15 into registry with the aperture in the rib 12, so that the key 16 may be inserted thus locking the parts firmly together. The upper forward face of the arm A and the lower forward face of the arm B are preferably beveled so as to insure a snug fit between these faces and the corresponding faces of the shackle C, thereby preventing 10 spreading of the arms A and B under pulling stresses.

In Figs. 5 and 6 I have shown a modification of my invention in which the rear portion 4' of the arm A' has been shortened 20 and provided with a central longitudinally extending recess 19. The lower arm B' has an upwardly extending portion 20 terminating in a hook or finger 21, which engages the lower wall 22 of the recess 19. In this 25 construction the pulling stresses are taken up by the vertically extending faces of the portions 4' and 20 of the parts A' and B' respectively.

In Figs. 7 and 8 I have shown another 30 modification of my invention in which the rear follower 23 is made integral with the upper arm A². Extending rearwardly from the follower 23 are flanges 24 connected at their rear ends by the transversely extending bearing member 25. The lower arm B² has an upwardly extending portion 26 which bears against the rear face of the lower end of the follower 23 and terminates in a hook shaped portion 27 intended to engage the 35 bearing member 25. After the upper arm A² has been placed in position with the coupler, front follower and shock absorbing mechanism therein, the hook 27 of the arm B² is slipped between the flanges 24 and 40 about the member 25. The arm B² is then rotated about the member 25 and secured at its forward end as described above.

In Figs. 9, 10, 11 and 12 I have shown a further modification of my invention in 50 which the rear follower 28 has rearwardly extending flanges 29 and transversely extending bearing members 30 integral with such flanges 29 and spaced apart from the rear face of the follower 28. Each arm A³ and B³ has a vertically extending portion 31 at its rear end terminating in a hook 32, which engages the corresponding bearing member 30 on the rear follower 28.

At the forward end of each arm is an apertured boss 33, on each side of which rearwardly extending apertured projections 34 on both top and bottom of the shackle C³ are intended to seat. The shackle C³ is secured to the yoke arms by passing a key 35

through the corresponding apertures in the 65 bosses 33 and projections 34 on the top and bottom of the yoke arms A³ and B³.

In Figs. 13 and 14 I have shown a further modification of my invention, in which the yoke arms A⁴ and B⁴ are inwardly offset at 70 their forward ends and the usual reinforcing rib is omitted, so that the yoke may be applied to cars in which there is a very limited vertical space for the yoke in the car underframing. The strap C⁴ is held in place 75 thereon by the usual key connection on the under side of the lower yoke arm and by the rearward extension of the lugs 15⁴ which bear against the under side of the lower yoke arm B⁴ and prevent the upper part of the 80 strap C⁴ from tilting or slipping off the upper arm A⁴.

It is obvious that various modifications may be made in the constructions which I have shown and described herein without departing from my invention.

What I claim is:

1. In a coupler yoke an upper and a lower arm, the said arms having a detachable connection at their rear ends and a securing 90 member for the forward ends of the yoke arms, said securing member having a fulcrum bearing on one arm and being adapted to be rotated thereabout into engagement with the other yoke arm. 95

2. In a coupler yoke an upper and a lower arm, the said arms having a detachable connection at their rear ends, said arms being enlarged at their forward ends, and a securing member having an opening therein of 100 less extent than the vertical distance between the outer faces of the enlargements on said arms, said securing member being adapted when the coupler is in position to be passed over one of said enlargements and then to be rotated about said enlargement 105 into engagement with the enlargement on the other arm.

3. In a coupler yoke an upper and a lower arm, the said arms having a detachable connection at their rear ends, said arms at their forward ends having their outer faces inclined, a shackle having inclined faces co-operating with the inclined faces on the upper and lower arms of the yoke and adapted to draw and hold the upper and lower arms of the yoke tightly together when the shackle has been moved into operative position. 110

4. In a coupler yoke, an upper and a lower arm, the said arms having a member securing their forward ends together, one of said arms having at its rear end integral trunnions adapted to seat in a socket in the other yoke arm, said trunnions and socket comprising a pulling engagement between the yoke arms substantially in line with the lower arm. 120 125

5. In a coupler yoke, upper and lower arms intended to engage on their inner faces the upper and lower faces of a coupler liner block, and a wedge member engaging
5 outer faces of the yoke arms and adapted to hold the inner faces of the yoke arms in position about the coupler liner block, one of the said arms having at its rear end integral trunnions adapted to seat in a socket in the other yoke arm, so as to provide a pulling engagement between the yoke arms.

WILLIAM BLACKMORE.
